UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

STEEL ROOF.

1,224,832.

Specification of Letters Patent.

Patented May 1, 1917.

Application filed January 15, 1916. Serial No. 72,254.

To all whom it may concern:

Be it known that I, PAUL M. BEARD, residing at St. Louis, Missouri, and being citizen of the United States, have invented certain new and useful Improvements in Steel Roofs, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings—

Figure 1 is a plan view of a portion of the roof showing the central and side panels thereof assembled.

Fig. 2 is a longitudinal section through a little more than one of the assembled roof units and is taken on line 2—2 of Fig. 1.

Fig. 3 is a transverse section through slightly more than one half of the roof, the section being in the plane indicated by line 3—3 of Fig. 1.

Fig. 4 is an enlarged fragmentary plan view of a portion of one of the roof joints and shows the method of joining the roof pans together to form a supporting arch for the roof.

Fig. 5 is a section taken on line 5—5 of Fig. 4.

Fig. 6 is an enlarged detailed section through one of the roof joints being taken on line 2—2 of Fig. 1.

Fig. 7 is a fragmentary side elevational view of the roof and illustrates the casting anchoring the roof sheets to one of the side plates of the car.

Fig. 8 is a detailed section showing the cap piece mounted upon roof pans.

Fig. 9 is another detailed section taken through a portion of one of the side plates and the end of the roof pan that rests thereupon.

Fig. 10 is a perspective view of a portion of one of the cap pieces, and

Fig. 11 is another perspective view of the roof pans but with the cap piece removed.

This invention appertains to modern steel roofs and has for an object the portions of

such a roof wherein extended ventilation spaces are present throughout the length of the car and between the positions of support of the roof.

In addition to the ventilation, flexibility 60 is given to the roof and the latter comprises sections so joined together that the roof is thoroughly water-tight.

Another object is to so form the elements of the sections or units and associate with 65 them auxiliary parts in such manner that a self-supporting roof structure results.

Other features of the invention will become manifest hereinafter and come within the scope of the present invention. 70

Referring to the drawings, 1 indicates a series of central panel sections having an end to end disposition and extending longitudinally of the car. The central panel sections are of channel-shaped cross section 75 and have depending flanges 2 along their sides. At their meeting ends the central panel sections are each provided with upstanding flanges 3, those of one section having vertical contact with the adjacent 80 flanges 3 of the next sections except in the end portions 3' of said flanges 3, said end portions 3' being bent with an appreciable curvature so that those of contacting flanges 3 are turned in opposite directions. 85

On each side of the central panel comprising the central panel sections 1 are side panels comprising a series of successive roof pans 4 of substantially the same length as the sections 1 of the center panel. In reality 90 the roof pans 4, which are of sheet metal, are of slightly less length than the central panel sections 1 so that the vertical flange of an angle 5 may extend between the juxtaposed upturned flanges 7 of adjoining 95 roof pans. As seen in Fig. 3 angle 3 is somewhat longer than the width of the center sections 1 but such excess of length is, preferably, only extensive enough to provide sufficient riveting area for the transverse flanges 7 of the roof pans 4, rivets 8 connecting said flanges with the upstanding flange of angle 5. The upper edge of the vertical flange of angle 5 in passing under the central panel sections 1 lies entirely 100 under the meeting line of the abutting upright flanges 3 of adjoining central panel sections as is shown in Fig. 6. Roof pans 4 are each provided with an inner upstanding flange 7a which is really a continuation 110

of the transverse roof pan flange 7, both flanges 7 and 7^a being merged by rounded corners. The inner flanges 7^a of roof pans 4 lie against the inner faces of the depending side flanges 2 of the center panel sections 1 and are secured thereto throughout the major portions thereof by rivets 9. The end portions 2^a of each depending side flange 2 of each center panel section 1 are deflected outwardly so that the opposite ends of each center panel section are flared as best seen in Figs. 4 and 11. The flared portions 2^a of the side flanges 2 of the center panel sections terminate at the outer faces 15 of the sides or depending flanges 10 of the joint cap 11. The outer edges of the extensions 3' of the upstanding center panel section flanges 3 bear against the inner faces of the depending side flanges 10 of the joint 20 cap 11 and between the terminals of the upstanding flange end portions 3' and the opposing terminals of the flared portions 2^a of the side flanges 2 of the center panel section are formed notches 12. A notch 12 is, therefore, present at each side of the joint and the depending flanges 10 of the joint cap have their inner edges inserted 25 into the notches 12, the joint cap thus becoming interlocked with the sections of the central panel at each joint.

As clearly seen in Fig. 4, the flanges 7 and 7^a of the roof pans 4 lie well within the depending flanges 10 of the joint cap 11 and the deflected flange portions 2^a of the center panel sections. The curvature of the extensions 3' of the upstanding flanges 3 of abutting center panel sections is such that water draining from said center panel sections will be deflected by the extensions 3' 35 of the flanges 3 into the roof pans 4, preserving the water-tight qualities of the joints between the units comprising the center panel sections 1 and the side panel sections comprehending the roof pans. The joint caps 11 each has a central portion 13 adapted to support running boards 14 which are secured to said center portions 13 of the joint caps by bolts or other suitable means. Running boards 14 are also afforded support by ribs 27 pressed upwardly in the central panel sections 1 as clearly shown in Fig. 1. Extending outwardly from each end of the running board supporting portion 13 are inverted U-shaped portions of said joint cap which contain the depending side flanges 10. These inverted U-shaped portions extend to the car side and gradually increase in width as they do so.

In the upper surface of each inverted 30 U-shaped portion of the joint cap is generated a continuously widening channel or groove 15 which is widest at the car sides. As said channel progresses outwardly, it also increases in depth and at its outer end 65 the depending flanges 10 of the joint cap

11 are secured to flanges 17 of an anchor casting 18 by rivets 19.

Castings 18 serve to anchor the roof structure to the side plates 16 of the car, each having a bottom flange 28 riveted to the bottom outstanding flange of the Z-shaped side plate 16. Between the flanges 17 the anchor casting web 20 is provided along its upper edge with a rib 20^a adapted to support the roof pans 4 through the contact of the bottom edges of their eaves flanges 23 resting upon said rib 20^a of the lower web 20 of anchor casting 18. Also between the vertical flanges 17 is an upper web 21 and from the rear of the latter inwardly extending fingers 22 engage and rest upon the roof pan sheets adjacent the eaves flanges 23 which depend from the outer edge of each roof pan 4. Said anchor castings 18 are each also provided with a top flange 24 which is conformed to the shape of the channel or depression 15 in the upper side of the joint cap 11.

The webs 20 and 21 of the anchor casting 18 lie in different vertical planes, the lower web 20 lying against the outer face of the web of side plate 16 and the upper web 21 being spaced outwardly therefrom. Said anchor casting webs 20 and 21 are also vertically spaced from each other to produce 95 the aperture 25 between them. The roof pan retaining fingers 22 being more narrow than the width of the lower and upper anchor casting webs 20 and 21, respectively, and the eaves flanges 23 of adjoining roof 100 pans being spaced apart an air passage is created, the inlet of which is the space 25 between the upper and lower webs 21 and 20, respectively, that is present between the fingers 22 and the edges of adjoining eaves 105 flanges 23. As seen in Figs. 1 and 3 this passage is maintained above the upper flange of the side plate 16 by depressions 26 progressively spaced in the body portions of the roof pans 4. The material in the bottom of said depressions 26 lies upon the top flange of the side plate 16 causing the body portions of the roof pans 4 to be spaced a suitable distance above said side plate top flanges, thereby maintaining the air passage 115 from the aperture 25 in the anchor casting 110 to the interior of the car at the joints.

It is also obvious that inasmuch as the eaves flange 23 of each roof pan is spaced from the outer faces of the webs of the side 120 plates 16 throughout the lengths of said side plates a series of successive air passages is created along the car sides throughout the lengths thereof.

Between successive depressions 26 the air 125 passage extends from the bottom of eaves flange 23 and exists between the inner face of said flange 23 and the outer face of the web of the side plate to the top of the latter as illustrated in Fig. 9. From thence the air 130

passage continues between the upper face of the top flange of the side plate 16 and the under face of the body portion of the roof pan to the car interior. Similar air passages, of course, are present between each anchor casting 18 and the next adjacent depression 26 on either side thereof.

From the foregoing it is evident that the improved roof is provided with a central panel and similar side panels on opposite sides thereof and that each of these panels are made up of sections. Each central panel section and the side panel sections, heretofore called roof pans, which are alined therewith transversely of the car, constitute a roof unit, and these units are arranged successively longitudinally of the car, and, as set forth, are secured together resulting in a strongly connected roof structure. It has also been made plain that adjoining roof units have their joints thoroughly weather-proofed, and that the joint caps are constructed to shed accumulated water and have portions which coöperate with ribs in the central panel sections to support the usual running boards.

Another novel feature developed, is the combining of the transversely arranged flanges 7 of the roof pans 4 with the relatively short, centrally located transverse angle 5 so that the resultant structure is the equivalent of a carline extending from one side plate 16 to the side plate 16 at the opposite side of the car.

35 The joining together of the opposite flanges 2 and 7^a of the central panel sections and the roof pans, respectively, creates a roof which extends from car side to car side, and as there are spaces between the inner faces of the eaves flanges 23 of the roof pans 24 and the outer faces of the webs of the side plates 16, the roof is possessed of flexibility transversely of the car.

45 What I claim is:—

1. In combination in a car roof, successively arranged roof units comprising connected central and side sections, successive side sections being rigidly connected near said central sections and contiguous ends of the central sections being unattached, and joint caps interlocking with and connecting said central sections in a relation-preserving manner.

2. In combination in a car roof, successively arranged roof units comprising central and side sections having rigidly connected substantially vertical side flanges, said central sections having unconnected opposing end portions, and joint caps projecting into and interlocking with contiguous central end portions and extending disconnectedly over connected portions of said side sections.

3. In combination in a car roof, side plates, successively arranged roof units com-

prising connected central and side sections of substantially the same extent longitudinally of the roof, the former and latter of succeeding units being, respectively, unattached and connected and caps extending over the joints of said units and being anchored to said side plates.

4. In combination in a car roof, side plates, successive roof units comprising central sections and side sections fastened to the sides of said central sections, the central and side sections of succeeding units being, respectively, unattached and connected, and joint caps interlocking with juxtaposed central section ends and being anchored to said side plates.

5. In combination in a car roof, successive roof units comprising central and side sections, the former of succeeding sections having upstanding portions and contiguous ends of said side sections being connected, and joint caps inclosing the connected side section portions and extending over and being supported by said upstanding portions and formed into running board saddle seats. 90

6. In combination in a car roof, successive roof units comprising central sections having depending flanges and side sections provided with upstanding flanges adapted to receive said depending flanges and to form 95 pans, portions of said central sections extending materially within the pan boundaries and away from the pan flanges and constituting fluid-deflectors.

7. In combination in a car roof, successive roof units comprising central sections having expanded tops and sides in their end portions and connected side sections, abutting upstanding flanges on the ends of adjoining central sections provided with water-deflecting extensions and caps inclosing the joints between said sections, extending over said central sections and projecting into the expanded top portions and between the expanded side portions of said central sections. 100

8. In combination in a car roof, opposing roof sheets extending toward but not to each other from opposite roof sides and each provided with a flange extending transversely 115 of a car and an intermediate member connected to the inner ends of the flanges of said opposing roof sheets and forming a carline therewith.

9. In combination in a car roof, successive roof sections on opposite car sides provided with flanges extending transversely of the roof but not to the longitudinal median line of the roof, whereby the inner ends of said flanges of the roof sections on one of the car sides are more or less spaced from the inner ends of the corresponding flanges of the roof sections on the opposite car side, and intermediate members each connected with said transverse flanges of an opposing 125

130

- pair of roof sections and forming a carline therewith.
10. In combination in a car roof, spaced longitudinally extending sets of successive side roof sections provided with longitudinal and transverse flanges, intermediate members connected with and connecting the transverse flanges of opposing side sections and forming carlines therewith, and central roof sections closing the space between said spaced sets of side sections and connected with said longitudinal flanges.
11. In combination in a car roof, spaced longitudinally extending sets of successive side roof sections provided with longitudinal and transverse flanges, central roof sections embracing said side section longitudinal flanges, and intermediate members each provided with a flange extending between the transverse flanges of contiguous side sections and under said central sections and forming a carline with the associated transverse flanges of said side sections.
12. In combination in a car roof, successive roof units comprising central and side sections, the former being provided with pressed running board supports and upstanding end flanges, and joint caps inclosing contiguous portions of adjoining side sections, extending over and being supported by said central section upstanding flanges and formed into running board seats.
13. In combination in a car roof, a side plate, roof sheet anchors supported thereby, roof sheets retained by said anchors, and joint caps housing contiguous roof sheet sides and being secured to said anchors and provided with water-discharging channels.
14. In combination in a car roof, a side plate, roof sheet anchors supported thereby, roof sheets retained near the side plate by said anchors, and joint caps housing contiguous sides of adjoining roof sheets and being provided with water-discharging channel portions and secured to seat portions in said anchors conformed to said cap channel portions.
15. In combination in a car roof, a side plate having an upper flange projecting inwardly from the main portion of said side plate, roof sheet anchors supported by said side plate, roof sheets extending entirely across the top of said side plate and directly supported by said side plate flange and retained by the same and said anchors, and joint caps housing and extending over contiguous edges of adjoining roof sheets and beyond the flange-supported edges of the roof sheets and also being secured to said anchors.
16. In combination in a car roof, a side plate having an upper flange, roof sheet anchors connected to said side plate, roof sheets provided with depressed water-discharging channels spacing the major portions of said roof sheets above said side plate flange and also having eaves flanges spaced from but adapted to move toward said side plate, ventilating passages being thereby created between the undersides of said roof sheets and said side plate between successive channels.
17. In combination in a car roof, a side plate, roof sheets having juxtaposed transverse portions and eaves flanges, a joint cap housing said juxtaposed portions, and a roof sheet anchor comprising a portion for attachment to said side plate, a joint cap seat, supports for the latter connecting the same and said attachment portion and roof sheet retaining portions adjacent said eaves flanges.
18. In combination in a car roof, a side plate, roof sheets having juxtaposed portions and eaves flanges, a joint cap for housing said juxtaposed portions, and a roof sheet anchor comprising a web for attachment to said side plate provided with a support for said eaves flanges, a joint cap seat, supporting portions for the latter and retaining means for said roof sheets.
19. In combination in a car roof, a side plate, successive roof sheets each having an eaves flange separated from that of the next roof sheet, caps housing joints between successive roof sheets, and roof sheet anchors each comprising spaced upper and lower webs in different vertical planes, the latter being secured to said side plate and adapted to support said eaves flanges, web connecting portions and fingers coöperating with said upper web to retain contiguous portions of adjoining roof sheets.
20. In combination in a car roof, a side plate, successive roof sheets passing thereover and having depending eaves flanges, roof sheet anchors each comprising connected spaced web portions one of which is secured to said side plate and members co-operating with said other web portion to retain contiguous portions of adjoining roof sheets, and means spacing said roof sheets above said side plate, there being a passage between said webs, eaves flanges, one of said web portions and the side plate and over the latter to the interior of a car.

In witness whereof I have hereunto set my hand in the presence of two witnesses.

PAUL M. BEARD.
